MIXING MACHINE

Paul Marienthal, Detroit, Mich.; National Bank of Detroit; and Benjamin Shwayder, executors of the estate of said Marienthal, deceased, assignors to The Sherwin-Williams Company, Cleveland, Ohio, a corporation of Ohio

Application October 16, 1948, Serial No. 54,897

12 Claims. (Cl. 259—64)

1

This invention relates to mixing machines and, in the particular embodiment shown, to machines for mixing and blending paint stocks such as are carried in paint shops or paint departments.

It has been the practice of automobile, appliance, and other manufacturers to sell their products with a number of differently colored finishes, the exact shade of which colors will not only vary from manufacturer to manufacturer but may vary between different models of a given manufacturer's product from year to year and from type to type. For example, an automobile manufacturer may not only change the selection of colors available for a given make of automobile from year to year, but the manufacturer may also have a wider selection of colors available for the "deluxe" models of a given year than for the "standard" models of that year; still further, the shade for the "deluxe" models may be slightly "richer" than the shade of substantially the same color used for the "standard" models of that year.

A result of the above practice is that automobile repair and refinishing shops are called upon to match a galaxy of colors and the cost of an inventory of any quantity of paints to match even the more common shades would be prohibitive. To overcome such an inventory problem, paint manufacturers supply such paint shops, or dealers and jobbers selling to such paint shops, with formula books and a line of stock finishes which precisely match the several color standards for the line. By blending exact proportions of the stock colors in accordance with the formula books, a precise match of the desired commercial color shade may be obtained.

Despite the possibility of exactly matching a desired color shade by blending stock color according to the formula for the color shade, such matches were not easily attained in actual shop practice. It was not only difficult to proportion the stock colors precisely, but the blending of the stock colors must be thorough. In addition, the stock colors must be thoroughly mixed before blending. Unless the pigment of the stock color is thoroughly dispersed in its vehicle before an amount of the stock color is poured out of its bulk container for blending with other colors into a batch of a matched color shade, not only will the desired color shade not be matched, but stock color remaining in the bulk container will be "off standard" for subsequent color matches. Satisfactory simple devices for measuring the amount of stock colors desired to be blended have been available for some time, but

heretofore no satisfactory machines for mixing and blending have been available.

Such mixing and blending machines as have been proposed heretofore usually required special containers and thus failed to solve the problem of providing a thoroughly mixed stock color which could be poured for measuring and blending from the standard bulk containers in which the stock colors were stored. Likewise, such proposed machines which were capable of simultaneously agitating a number of stock colors or blends had to be stopped in order for one container to be removed from the machine or to be emptied. Since the paints and lacquer to be mixed or blended are preferably agitated gently and slowly, in such machines it was difficult to keep track of the interruption necessary to load in a new batch or to remove one batch of color from the several being mixed simultaneously. Such interruptions not only reduced the productive capacity of the machine over a period of time but resulted either in some batches being under-mixed or overmixed; overmixing, so long as it was gentle, did not harm the color but did further reduce the effective capacity of the machine. Another fault of such prior proposed machines was that they would not efficiently handle both large and small batches of color.

It is the object of this invention to provide a color mixing and blending machine which overcomes the above outlined disadvantages of the proposed prior art machines. It is an advantage of this machine that stock colors in standard bulk quart and gallon containers may be mixed simultaneously in the machine, the quart and gallon containers being interchangeably mountable for mixing in the machine. This interchangeability of quart and gallon containers likewise permits, of course, large and small amounts of colors to be blended in the machine.

A particular advantage of this machine is that a container for colors to be mixed or blended in the machine may be loaded into or removed from the machine without stopping the machine or interrupting the simultaneous mixing or blending of other colors. This particular advantage is obtained by a novel automatic coupling in the drive for the mixing head and it is, therefore, a further object and advantage of this invention to provide an automatic, positive drive coupling between a mixing head or similar device and the drive therefor, which coupling permits substantial misalignment (i. e., eccentricity and/or endwise or axial displacement) between the driving and driven shafts while also permitting the cou-

pling to be disconnected by simply removing the coupling elements from the vicinity of each other. The coupling may also be connected by simply placing the coupling elements so that they are within the driving range or vicinity of each other. Coupling and uncoupling may be accomplished without stopping the driving shaft; there is no coupling control mechanism to be operated before the coupling can be released or engaged.

Other and further objects and advantages will be apparent from the following specification, claims and drawings, in which:

Fig. 1 is a front elevation of a machine made according to the invention.

Fig. 2 is a top plan view of the machine shown in Fig. 1, but with the motor hood removed.

Fig. 3 is a vertical section taken along the line 3—3 of Fig. 1.

Fig. 4 is a horizontal section taken along the line 4—4 of Fig. 3 and showing the coupling in a driving connection.

Fig. 5 is an enlarged detail elevation, partly in section, taken along the line 5—5 of Fig. 1, showing the position of the coupling elements at the instant a paint container has been placed in the mixing machine.

Fig. 6 is an enlarged detail of the coupling elements shown in Fig. 5 but showing the relative position of the driving and driven elements of the coupling as shown in Fig. 5 after the driving shaft has advanced.

Fig. 7 is a detail similar to Figs. 5 and 6 but showing the driving element advanced to the driving position as shown in plan in Fig. 4.

Fig. 8 is a detail horizontal cross-section taken along the line 8—8 of Fig. 1.

Fig. 9 is a detail vertical cross-section taken along the line 9—9 of Figure 8.

The embodiment of this invention as shown in the drawings comprises a structure having an open-front section 10 partitioned by a plurality of hollow vertical walls 11 to provide the paint container-receiving compartments 12. In the particular embodiment shown there are six compartments 12 designated as 12—1 to 12—6, as indicated. The rear wall 13 of the section 10 is provided with suitable openings in each of the compartments 12, through which openings there may protrude the pouring spouts of the mixing heads for the paint containers. The ceiling 15 for the several compartments 12 is a longitudinal channel which also serves as a chassis for the several driving spindles 25 and as a support for the motor base 21 of the motor 20 and for the base 23 of the speed-reducer 22, both mounted in the hood 16 above the section 10.

The drive for the several driving spindles 30 comprises the motor 20 which runs constantly when connected to a suitable source of power. The motor 20 drives the speed-reducer 22, as by the V-belt drive shown. The speed-reducer 22 in turn drives the several spindles 25 by means of its driven sprocket 24 and the sprocket chain 26 which, in turn, drives the several aligned spindle sprockets 27 keyed to the spindles 25. As best shown in detail in Fig. 5, each spindle 25 is journaled in spindle bearings 28 fastened to and extending vertically through the ceiling 15. To maintain the sprocket chain 26 taut, a conventional idler sprocket 29 is employed. To hold the chain 26 against the sprockets 22 in the run of the chain over the aligned sprocket, a back-up bar 19 may be employed.

The coupling 30 for each driving spindle 25 and the mixing heads 40 of the paint containers

75 for paint to be mixed in my machine comprise a horizontally-extending driving key 31 and a driven pin bar 32 carrying horizontally spaced, vertically extending restraining pins 33. The key 31 is provided with the wings 34 by which the key is hung from the spindle 25 on the pivot pin 35 carried thereby. Thus, except for the bias exerted by gravity (or by biasing springs which may be employed), the key 31 is freely pivotedly mounted on the horizontal pivot pin 35 for movement in a nearly circular arc concentric with the pivot pin 25, said vertical arc lying in a plane perpendicular to the axis of the pivot pin 35. It will be evident from Figs. 4 to 7 that, unless the key 31 is restrained from swinging in the said vertical arc, the key 31 is incapable of transmitting torque from the spindle 25 but, instead, will swing up and ride over an obstruction terminating within the locus of the solid of revolution described by the key as it, hanging from the pivot pin 35, is turned by the spindle 25.

The driven element of the coupling 30, i. e. the pin bar 32, is designed to restrain the key 31 from swinging upwardly when the pair of pins 33 extend into the locus of the solid of revolution described by the rotating key 31, whereby a couple, as shown in Fig. 4, will be exerted on the key 31 and, thus, torque will be transferred from the spindle 25 through the pivot pin 35, wings 34, key 31 and pin 33 to the bar 32. Each bar 32 is mounted on the shaft 41 of a mixing head 40, so that the pins 33 are oppositely disposed with respect to the axis of the shaft 41. The mixing heads 40 may be of any suitable design, the ones shown, 40G and 40Q, being made according to my Design Patents D. 125,776 and D. 125,777, granted March 11, 1941, the mixing heads shown in the embodiment differing from those shown in my design patents only in that the manual stirring crank shown in the design patents is replaced by the pin bar 32. The mixing heads 40G and 40Q are used, respectively, on standard gallon and quart containers 50G and 50Q. The standard containers 50 have raised, wide-mouthed pouring openings on which the mixing heads 40 may be clamped by the cam locking levers 43. As indicated in Fig. 1, each mixing head 40 carries a suitable paddle shaft 44 which extends into a container 50; each mixing head 40 is also provided with a pouring spout 45 which extends into the openings 14 when the containers 50 are positioned beneath the spindles 25 so that the mixing heads may be driven thereby. A suitable closure 46 is pivotally mounted on the spouts to prevent paint from splashing out of the container during mixing. The mixing paddle shaft 44 may be directly driven by the mixing head shaft 41 or the shaft 44 may be driven through suitable gearing (not shown).

The particular disclosed embodiment of my machine is designed to accommodate quart and gallon sizes of stock containers in which the diameter of the cylindrical quart containers happens to be about the same dimension as the thickness of the gallon containers, which have a rectangular cross-section. The quadrupled capacity of the gallon containers is accounted for in part by the greater cross-sectional area, but is largely due to the increased vertical height of the gallon containers. Since the effectiveness of the couplings 30 depends upon bar pins 33 being maintained in, and preferably substantially centered within the locus of the key 31, the hinged brackets 60 constitute a simple and effective de-

vice for locating the bar pins 33 when carried on a quart container so that the pins will be held at the same height as when mounted on a gallon container. Thus, the brackets 60 permit each compartment 12 to be used interchangeably for quart as well as gallon containers.

As shown in Fig. 1 and in detail in Figs. 8 and 9, a hinged bracket 60 is comprised of a leaf 61 provided with cam ends 62 and, on its outer edge, a long notch 63 providing projections 61 adapted to receive and, in cooperation with a similar bracket on the opposite partition wall 11, center the bottom of a quart container. Each bracket 60 is hinged in the disclosed embodiment by means of an offset central lug 64 and end lugs 65 bent to an acute angle with respect to the leaf 60, the lugs 64 and 65 extending into corresponding slots in the supporting partition 11. As shown in compartments 12-1, 12-4 and 12-5 in Fig. 1, the brackets 60 normally swing outwardly from the partitions 11 and are thus positioned to support a quart container at the proper height to permit the pin-bar on the mixing head to be engaged by the key of the coupling (See container 50Q in compartment 12-2, Fig. 1). In this normal position of the leaf 61, outward hinging thereof is limited by the angle of the lugs 65, which engage the adjacent wall of the partition 11. The offset central lug 64 prevents the bracket 60 from being removed from the wall of the partitions 11. When a gallon container 50G is inserted into a compartment, the outer cam end 62 is engaged by the sides of the container, whereby the brackets 60 are hinged upwardly to a position parallel to the walls of the partition 11, as shown in compartments 12-3 and 12-6 in Fig. 1 and in dotted lines in Fig. 9. Upon removal of a gallon container 50Q from a compartment, the hinged brackets 60 automatically drop outwardly, where they are again ready to support a quart container or to swing against the partition 11, if the next container inserted in the compartment should be a gallon container. While only one pair of brackets 60 is shown mounted on opposite walls of a compartment 12, it is to be understood that additional pairs may be employed to support other containers, of different heights, in the proper position to permit the coupling 30 to engage. Such additional pairs of hinged brackets may be wider if the other containers are of a lesser diameter or thickness than the containers shown in Fig. 1.

Operation of machine and coupling

With the motor 20 constantly driving the several spindles 25, my machine is ready to receive a paint container 50 carrying a mixing head 40 in any vacant compartment 12. As shown in Fig. 1, the coupling 30 for the container 50G in compartment 12-3 is in the driving position and is driving the mixing head 40G to mix the paint in that container; the container 50Q in compartment 12-2 has been inserted a sufficient period of time to permit the key 31 to fall between the pins 33 so that, upon a further quarter turn of the driving spindle carrying that key, the key 31 and pins 33 will be in their driving position. The container 50Q shown in compartment 12-6 in Fig. 1 has just been inserted and approximately 300° rotation by the shaft 25 in that compartment will be required before the coupling in that compartment will be engaged.

Figs. 5, 6 and 7 show the action of the key 31 in effecting an automatic coupling when a container carrying a mixing head 40 is inserted in

a compartment. Assuming that a pin bar 32 is turned on the mixing head so that the pins 33 strike the key 31 broadside as the container is inserted, then the key 31, pivoting on the pivot pin 35, will be moved slightly upwardly and out of its normal driving zone comprising a disk-shaped volume generated by the key when it intersects the axis of the spindle 25. As this spindle rotates, the key will ride upon the pins until it approaches a position transverse to the pins 33. The key will then clear the pins and return to its normal driving zone under the biasing influence of gravity. If the first pin 33a striking the key is advanced so that it strikes the trailing side of the rotated key, as shown in Fig. 5, such an initial contact of the coupling element will require the greatest rotation of the spindle 25, i. e. approximately 300°, before the coupling 30 will be in driving engagement. With an initial contact of the coupling element as shown in Fig. 5, continued rotation of the spindle 25 will allow the key 31 to fall until it is nearly perpendicular and rests against both pins 33a and 33b. Thereafter, continued rotation of the spindle will cause the key 31 to ride up on the pins 33b until the key reaches the position shown in Fig. 6, where it is ready to fall to the perpendicular position between the pins, as shown in dotted lines. When the key has fallen to a perpendicular position between the pins 33, continued rotation will carry the key to the driving position shown in Fig. 7.

As should now be apparent, considerable eccentricity of the spindle 25 and the mixing head shaft 41 is permissible, since the key is free to slide on the pins while the coupling 30 is engaged, the greater length of the key with respect to the spacing of the pins determining the permissible eccentricity of the driving and driven shafts. Longitudinal displacement of the two shafts is also permissible, the height of the key determining the maximum longitudinal displacement. As indicated in Fig. 6, the height and spacing of the pins 33 should be such that, when the pin bar is at its minimum axial distance from the end of the spindle 25, the key 31 should be free to fall to its perpendicular position between the pins when the pin bar and key are perpendicular to each other.

Since the coupling 30 permits considerable eccentricity and axial displacement of the shafts, skew misalignment is also permitted, being the sum of component of eccentricity and axial displacement. If the misalignment of the driving and driven shafts exceeds the permissible limits of eccentricity and axial displacement, the coupling will, of course, either not engage or will become disengaged. Thus, to disengage a coupling 30 and to stop the mixing of any given container 50, the container is simply taken out of its compartment without stopping the machine and without interrupting the mixing of stock paints or blending of mixed stock paints in other compartments.

In the particular embodiment shown, the keys 31 are biased by their own weight so that they will tend to fall to a position transverse to the vertical axes of the spindle 25. If the elements of the coupling were reversed, i. e., if the pin bar were carried by the spindle 25 and the key by the shaft 41, the key should be biased, as by a spring, to tend to assume the said transverse position. Such a biasing spring should also be employed where the design of the machine employing my novel coupling does not permit the driving and driven shafts to be vertical.

From the foregoing it should be apparent that my invention is not limited to the particular embodiment disclosed but may be modified in whole or in part or adapted to other uses by those skilled in the art without departing from the scope of this invention as set out in the following claims.

What is claimed is:

1. In a mixing machine comprising a rotatable driving spindle, a drive therefor, a removable container for material to be mixed in said machine, a mixing head mounted on said container, a rotatable shaft for operating said mixing head, a releasable coupling connecting said spindle and said shaft comprising a key member carried by one of said rotatable elements and pivoted for pivotal movement about an axis transverse to the axis of said one rotatable element, a coupling member carried by the other of said rotatable elements and cooperating with said key member, said coupling element being movable relative to said key member to engage and to disengage said coupling element and key member while maintaining the rotation of said driving spindle.

2. In a mixing machine for mixing materials in a plurality of containers independently insertable and removable without interrupting the mixing in other containers, a plurality of driving spindles, means to drive said spindles continuously, a plurality of compartments for receiving containers of liquid to be mixed in the machine, each of said containers carrying a mixing head provided with a coupling element to drive said mixing head, a key member carried by each of said spindles and pivoted for pivotal movement about an axis transverse to the axis of its associated spindle, each of said key members being adapted to engage and drive its associated coupling element while maintaining the rotation of said driving spindles when said coupling element is placed within the driving zone of said key member, and means to support the containers in a position causing said coupling elements and key members to engage.

3. A machine for simultaneously and interchangeably mixing materials in containers of a series of heights comprising a structure having a plurality of compartments, a driving spindle depending into each of said compartments, means for driving all of said spindles simultaneously, a key member of a releasable coupling carried by each of said spindles and pivoted about an axis transverse to its associated spindle, each of said key members defining a driving zone in which a coupling element carried by a mixing head mounted on a container will be engaged and driven while maintaining rotation of all of said spindles when said coupling element is supported in said zone, and means for supporting in said compartments a container of any one of the heights of the series to locate said coupling element on the container within the driving zone of the key member element in the compartment, whereby the contents in several containers of different heights may be mixed simultaneously and a container of a given height of the series may be supported in any one of the plurality of compartments during such simultaneous mixing.

4. In a machine for mixing materials in containers of a series of heights, a compartment defined by a floor, a ceiling, and a side wall, a driving spindle extending from said ceiling into

said compartment, means for driving said spindle, a first coupling element carried by said spindle and defining a driving zone in which a second coupling element on a mixing head mounted on top of a container will be engaged and driven by said first coupling element, the height of said driving zone above said floor being of such a height as to cause the second coupling element to be engaged and driven by said first coupling element when said mixing head is mounted on a container of maximum height, a hinged bracket carried by the side wall of said compartment, said hinged bracket being pivotable to a first position against said side wall to permit a container of maximum height to be placed on said floor and support said second coupling element in engagement with said first coupling element, said hinged bracket being further pivotable to a second position at an angle with respect to said wall to support a second container of less than maximum height at the elevation above said floor at which a second coupling element on such a second container will be engaged and driven by said first coupling element.

5. A machine as defined in claim 4 in which said hinged bracket comprises a leaf having a cam-shaped end portion whereby, when said bracket is hinged to said second position and would otherwise obstruct the sliding of a container along said side wall, said cam-shaped end portion may be engaged by the side of a container being slid along said wall to automatically cam said bracket to its said first position against said wall.

6. A machine for simultaneously and interchangeably mixing paint in stock quart and/or gallon containers of a type having a substantially common horizontal dimension but in which the vertical height of the gallon container is greater, said machine comprising a structure having a plurality of compartments, each defined by a ceiling, a floor and parallel side walls, a driving spindle depending into each of said compartments, means for driving said spindles simultaneously, a first coupling element carried by each of said spindles and defining a driving zone for a second coupling element mounted on a mixing head carried by a container received in the compartment, the height of the said driving zone above the floor of said compartments being the height at which said second coupling element may be engaged by said first coupling element to drive said second coupling element and said mixing head in one direction when said mixing head is mounted on such a gallon container, and hinged brackets horizontally pivotally mounted on opposite side walls of said compartments and pivotable from a greater angle to the supporting side walls at which the distance between the adjacent edges of the brackets is less than the said common dimensions of the containers to a lesser angle at which the distance between the most closely adjacent portions of said brackets is greater than said common dimension, the said brackets being mounted on the side walls at an elevation to support a quart container at a height at which a mixing head mounted thereon will permit a second coupling agent carried thereby to be engaged and driven by said first coupling agent.

7. A machine as defined in claim 6 in which said brackets are provided with cam shaped edge portions whereby, when a gallon container is slid into a compartment, the walls of said con-

tainer will cam a bracket resting at said greater angle to said lesser angle.

8. A machine as defined in claim 7 in which said brackets are provided with projections to center substantially the second coupling element carried by the mixing head mounted on a quart container when a quart container is supported on said brackets.

9. In a mixing machine provided with compartments for removably receiving containers carrying a mixing head to be driven by a continuously rotating driving shaft in said machine, a releasable coupling for establishing a torque transmitting connection between said driving shaft and a driven shaft in said mixing head comprising a key element pivotally supported beyond the end of one shaft about a pivotal axis transverse to and intersecting said shaft, said key element being biased to assume a normal location beyond the end of said shaft, whereby, when said shaft is rotated, said key element will define a driving zone, a restraining element carried by the second shaft, projections on said restraining element spaced a distance less than the length and greater than the width of said key element, whereby said shafts may be moved axially and eccentrically away from each other to release the coupling and, when maintained in substantial alignment permitting said projections to extend into said driving zone, will establish a driving connection between said shafts for rotation of said driven shaft only in the direction of rotation of said driving shaft.

10. A coupling as claimed in claim 9 in which said restraining element comprises a bar mounted on the end of the second shaft extending transversely thereof and said projections comprise pins mounted on said bar, said pins being located oppositely and equidistant from the intersection of the axis of said shaft by said bar.

11. A coupling for a machine of the class described comprising a key member and means to pivot said key member on an axis parallel to the length thereof and a restraining member

provided with a pair of projections spaced from each other a distance less than the length of said key member but greater than the width thereof and means to mount said restraining member on a shaft to position said projections beyond the end of the shaft.

12. A releasable coupling for establishing a torque-transmitting connection between substantially aligned vertical shafts, said shafts being movable eccentrically and axially away from each other, comprising a key pivotally mounted to hang below the end of the upper of said shafts and extend transversely thereof to generate its normal disk-shaped driving zone when said upper shaft is rotated, a pair of transversely spaced pins mounted to extend above the lower of said shafts, said pins being spaced a distance less than the length of said key and greater than the width of said pins, and no one of said keys being disposed radially from said lower shaft a distance greater than the length of said key, whereby, when said shafts are substantially aligned and said pins extend into said driving zone, said key will fall between said pins to establish a driving connection between said shafts and the connection may be released by moving said shafts away from each other.
